UNITED STATES PATENT OFFICE.

JOHN ELSTON RHODES, OF NEW YORK, N. Y.

GARMENT-SECURING DEVICE.

No. 822,076.

Specification of Letters Patent.

Patented May 29, 1906.

Application filed May 22, 1905. Serial No. 261,593.

To all whom it may concern:

Be it known that I, JOHN ELSTON RHODES, a citizen of the United States, and a resident of the city of New York, borough of Bronx, in the county and State of New York, have invented a new and Improved Garment-Securing Device, of which the following is a full, clear, and exact description.

My invention relates to devices for securing garments in place, and more particularly to those adapted for use in connection with skirts and shirt-waists. Its principal objects are to provide such a device which will hold the skirt from sagging and the waist from crawling and which will also draw down the front of the waist to give the pointed effect.

Reference is to be had to the accompanying drawings, forming a part of this specification, in which similar reference characters 20 designate similar parts in all the views.

Figure 1 is a perspective view of one embodiment of my invention. Fig. 2 is an enlarged transverse section through the connecting-clasp on the line 2 2 of Fig. 1. Fig. 3. 25 is a front elevation of one of the companion clasps, and Fig. 4 is a section on the line 4 4 of Fig. 3.

The numeral 10 designates a belt which has its ends separably connected by a clasp 11. This clasp comprises a plate having near one side parallel toothed slots 12 12 to receive and secure one end of the belt. At the opposite side is a slot 13, which may be engaged by a hook 14, fixed to the opposite 35 extremity of the belt. The plate is curved to conform in a general way to the waist of the wearer, and therefore having its concave side turned outwardly. The slots at the opposite sides of the plate may be inclined with 40 relation to the central axis, they being shown as converging toward the top to better enable the belt to follow the waist-line. In the plate above the ends of the belt is an opening 15 of substantially triangular form, but with 45 the apices rounded and the base situated just above the openings, and from the apex opposite the base extends a contracted portion 16. The general contour of the upper part of the plate is similar to that of the opening, there 50 being left about it a wall of suitable thickness. At the upper end of the clasp 11 diverging hooks 17 17 overhang the concave side of the plate and serve to engage the band of the skirt. The bottom of the plate below 55 the belt is bent to surround a portion of an attaching device, this, as illustrated, being in

the form of a safety-pin 18, the movable portion 19 of which is left free to engage the corset.

Mounted upon the belt are clasps 20, 60 which are conveniently six in number and each of which is furnished by a plate provided with parallel slots 21 21, through which the belt passes. In each plate, above the slots, is an opening 22 similar to that of the 65 clasp 12 and having a like upwardly-extending contracted portion 23. The clasps 20 are also curved, and at the outer face, upon each side of the portion 23, is a projection 24, these projections extending toward the upper ends of the clasps and being reduced or pointed. They are conveniently formed by striking up tongues from the body of the plate.

In use the belt is placed about the waist of 75 the wearer, its length being adjusted by slipping it through the slots 12 and it being fastened in place by the insertion of the hook 14 in the slot 13. The pin 18 is attached to the corset to hold the clasp 11 down over the abdomen at the center of the front of the waist, while the clasps 20 are slipped along the belt to secure such a distribution as will best suit the particular person employing the device. Portions of the shirt-waist are now introduced 80 through the openings 15 and 22 from the inner sides of the clasps and drawn up into the contracted portions. The skirt is placed over the clasps at such a height that the band may be engaged by the projections. 85 Then upon drawing the outer belt about the waist the band is forced against the projections, and thus prevented from sagging. At the same time the pressure of the skirt-band upon the portions of the waist protruding 90 through the openings locks these against accidental disengagement. To hold the skirt from rising at the front, the band is slipped beneath the hooks 17, and this central portion of the shirt-waist is drawn down to produce a point or dip. It should be noted that 95 the garments need be in no wise altered to adapt them for use in connection with my improved securing device and that it may be applied without sewing.

Having thus described my invention, I claim as new and desire to secure by Letters Patent—

1. A garment-securing device comprising a belt, a clasp mounted upon the belt and being provided with an opening to receive a portion of a garment, garment-engaging

- means situated on said clasp adjacent to the opening, and a connector for the ends of the belt, said connector having an opening to receive a part of a garment and also being provided with a garment-engaging hook outside of said opening.
2. A garment-securing device comprising a belt, a clasp mounted upon the belt and being provided with an opening to receive a portion of a garment, garment - engaging means situated adjacent to the opening, and a connector for the ends of the belt, said connector having an opening to receive a part of a garment and at its opposite ends a hook and a safety-pin.
3. A garment-securing device comprising a belt, a clasp mounted on the belt, and a connector for the ends of the belt, said connector having an opening to receive a part of the garment, and provided at its opposite ends with a hook and a safety-pin.
4. A garment-securing device, comprising a belt, and a connector for the ends of the belt, said connector having an opening to receive a part of a garment, and being provided at its upper and lower ends respectively with a hook and a safety-pin. 25
5. A garment-securing device comprising a plate provided with belt-openings and an opening having a contracted portion, a hook projecting from the plate at the end of the contracted portion, and an attaching device mounted upon the plate at the opposite side of the openings from the hook. 30

In testimony whereof I have signed my name to this specification in the presence of two subscribing witnesses.

JOHN ELSTON RHODES.
